(57) **CLAIM**

We claim, the ornamental design for a confectionary slab article, as shown and described.

DESCRIPTION

FIG. 1 is a perspective view of a confectionary slab article, showing our new design in an exemplary embodiment; FIG. 2 is a side elevation view of the embodiment shown in FIG. 1, the opposite side view being a mirror image thereof; FIG. 3 is a top plan view of the embodiment shown in FIG. 1, the bottom view being a mirror image thereof; FIG. 4 is a front elevation view of the embodiment shown in FIG. 1, the back view being a mirror image thereof; FIG. 5 is a perspective view of a confectionary slab article, showing our new design in an exemplary embodiment; FIG. 6 is a side elevation view of the embodiment shown in FIG. 5, the opposite side view being a mirror image thereof; FIG. 7 is a top plan view of the embodiment shown in FIG. 5; FIG. 8 is a bottom plan view of the embodiment shown in FIG. 5;

FIG. 9 is a front elevation view of the embodiment shown in FIG. 5, the back view being a mirror image thereof;

FIG. 10 is a perspective view of a confectionary slab article, showing our new design in an exemplary embodiment;

FIG. 11 is a side elevation view of the embodiment shown in FIG. 10, the opposite side view being a mirror image thereof; FIG. 12 is a top plan view of the embodiment shown in FIG. 10;

FIG. 13 is a bottom plan view of the embodiment shown in FIG. 10; and,

FIG. 14 is a front elevation view of the embodiment shown in FIG. 10, the back view being a mirror image thereof.
